UNITED STATES PATENT OFFICE.

JOHN P. VORDERMARK, OF INDIANAPOLIS, INDIANA.

BUTTON-POLISHER.

SPECIFICATION forming part of Letters Patent No. 725,897, dated April 21, 1903.

Application filed February 11, 1903. Serial No. 142,847. (No model.)

To all whom it may concern:

Be it known that I, JOHN P. VORDERMARK, a citizen of the United States, residing at Indianapolis, in the county of Marion and State 5 of Indiana, have invented new and useful Improvements in Button-Polishers, of which the following is a specification.

My invention relates to certain new and useful improvements in button cleaning and 10 polishing devices; and it consists in a portable rotary brush hereinafter more fully set forth, and particularly pointed out in the claims.

The object of my invention is to provide a cheap, compact, durable, and portable device 15 for rapidly cleaning and polishing buttons on uniforms, and is particularly designed for the use of military men or such others that are required to preserve the luster of the buttons of their uniforms; and a further object of this invention is to so construct this 20 device that the same may be readily used and applied to buttons on uniforms when the latter are either on or off the wearer. I attain these objects by means of the device illus- 25 trated in the accompanying drawings, in which similar numerals of reference designate like parts throughout the several views.

Figure 1 is a side view of the device, partly 30 in section, and taken through the line A B. (See Fig. 2.) Fig. 2 is a plan view of the same, and Fig. 3 is an end view showing the button hook and shield.

A rotary polishing - brush 1, having the 35 bristles 2, is secured on the shaft 3, which latter is journaled in the bearings 4 and 5, formed integral on the inclosing casing 6, and said shaft is adapted to turn and to slide longitudinally in said bearings. A keyway 7 extends longitudinally of said shaft 3, and a bevel-pinion 8 is mounted on said shaft 3 and 40 is caused to turn therewith by means of the key 9, which engages the keyway 7 of said shaft 3 and is adapted to freely slide therein.

On the projecting reduced end 10 of the 45 shaft 3 or the end opposite the brush 1 is provided a push-button 11, by means of which the shaft 3 is moved longitudinally to cause the brush 1 to approach and to contact with the button to be cleaned and polished. A 50 spiral spring 12 surrounds the shaft 3 and contacts with one side of the pinion 8 at one of its ends and with the stop-pin 13 at its op-

posite end, and said spring 12 is provided for the purpose of not only yieldingly retaining said pinion 8 in position on said shaft 3 and 55 against the bearing 4, but also for returning said shaft 3 and the brush 1, secured thereon, into normal position when the push-button 11 is released. A removable cover 14 is screwed or otherwise secured on the casing 6, and centrally on said cover 14 and integral therewith is formed the hub-bearing 15, in which is journaled the crank-shaft 16. On the inner projecting end of said shaft 16 is keyed or otherwise secured the bevel-wheel 17, which 60 latter meshes with the smaller bevel-wheel 8 to drive the latter to rotate the shaft 3 and the brush 1, secured thereon, at an increased velocity. A crank-handle 18 is secured on the exterior projecting end of the crank-shaft 70 16, by means of which crank-handle the shaft 3 is driven.

A gripping-hook 19 is formed integral on the back of the casing 6, and the same is provided for the purpose of securely holding the 75 device while using the same.

The guard-hook 20, provided with the engaging slot 21, has the hub 22 formed integral on its arm 23, and the said hub 22 is drilled to receive the prolonged end of the 80 bearing 4, on which latter said hook is adjustably secured by a set-screw 24, so that the said hook 20 may be moved and adjusted into position nearer to or farther from the brush 1, according as the buttons to be operated 85 upon vary in thickness.

The practice of my invention I will now proceed to describe. Suppose, for example, the buttons sewed or otherwise permanently secured on a military or other uniform. Then 90 without the use of any special device it is absolutely necessary to exercise great care while polishing the buttons in order to prevent the polish being rubbed on the cloth of the garment, which would render the same 95 unfit for further use, and for the purpose of avoiding this extra care and trouble I have constructed this invention of a button-polisher, which I apply as follows: The hook 20 is first applied to the button between the 100 garment and the under side of said button to engage the shank or neck of the latter and to hold said button firmly while being polished. The operator now grasps the handle

19 with one hand and presses the push-button 11 to cause the bristles 2, which has had a suitable polishing powder or paste applied, of the brush 1 to contact with the face of the 5 button. The said brush is rotated while in contact with said button by the handle 18, and when said button has been thoroughly cleaned and polished the push-button 11 is released and the hook 20 of the device is re- 10 moved, and the device is again ready for another operation.

Having thus fully described this my invention, what I claim as new and useful, and desire to cover by Letters Patent of the United 15 States therefor, is—

1. In a button-polishing device, the combination with a gear-inclosing casing, shaft-bearings formed integral with said casing, a shaft adapted to turn and to slide longitudinally in said bearings and suitable gearing inclosed in said casing whereby said shaft is 20 rotated, of a button-engaging hook, a rotary brush on the end of said shaft and situated intermediate said hook and said casing and 25 means for traversing said shaft to move said brush nearer to or farther from the object to be polished.

2. In a button-polishing device, the combination with a gear-inclosing casing, shaft-bearings formed integral on said casing, a shaft adapted to turn and to slide longitudinally in said bearings and suitable gearing inclosed in said casing whereby said shaft is 30

rotated, of a button-engaging hook adjustably secured to said casing, a rotary brush 35 on the end of said shaft and situated intermediate said hook and said casing and a push-button on the end of said shaft opposite to the brush end thereof.

3. In a button-polishing machine, the combination with a gear-inclosing casing, a removable cover, shaft-bearings on diametrical opposite sides of said casing and a shaft-bearing having its axis at right angles with the former shaft-bearings, a shaft adapted to 40 turn and to slide longitudinally in the former or main bearings, a crank-shaft in said second bearing, a gear in the end of said crank-shaft a gear on said traversing shaft and situated to mesh with the former gear, and a 45 spring situated intermediate said second gear and the casing and surrounding said main traversing shaft, of a button-engaging hook adjustably secured on said casing, a rotary brush on one end of said traversing shaft intermediate said hook and said casing and a push-button on the opposite end of said traversing shaft, substantially as and for the purpose set forth.

In testimony whereof I have hereunto set 50 my hand in the presence of two subscribing witnesses.

JOHN P. VORDERMARK.
